UNITED STATES PATENT OFFICE.

MAX MENKIN, OF NEW YORK, N. Y.

BUTTON-ASSEMBLING DIES.

Application filed May 14, 1926. Serial No. 109,025.

This invention relates to button assembling dies, and has for its primary object to provide an improved die for assembling the parts of covered buttons whereby quantity 5 production may be greatly expedited and the parts accurately assembled with a less number of operations of the die mechanism and less manual labor than heretofore required.

10 To the above end, my present improvements are essentially characterized in that there is provided the usual upper and lower die members while in conjunction with such die members I employ a reversible die member. In other words, this die member is 15 adapted to be operatively arranged between the upper and lower die members in different operations of the device with either end of said intermediate die member in opposed relation to said upper and lower die members.

More particularly, it is the purpose of my present improvements to provide the intermediate reversible die member with opposite end portions which are of identically 25 the same construction but which will, nevertheless, properly cooperate in either position of the reversible die member with the upper and lower die members with which it 30 is arranged and in conjunction therewith will assemble the parts of the button with the covering material securely confined thereon.

With the above and other objects in view, the invention consists in the improved button assembling die, and in the form, construction and relative arrangement of its several parts as will be hereinafter more fully described, illustrated in the accompanying drawings and subsequently incorporated in 40 the subjoined claim.

In the drawings, wherein I have illustrated one simple and practical embodiment of the invention, and in which similar reference characters designate corresponding parts 45 throughout the several views,—

Figure 1 is a vertical sectional view illustrating the initial step in assembling the parts of the button;

Fig. 2 is a similar view showing the next 50 succeeding operation with one of the button parts shaped to its final form;

Figs. 3 and 4 are views corresponding with Figs. 1 and 2 and illustrating the assemblage of the parts constituting the other half of 55 the button;

Figs. 5 and 6 are vertical sectional views

showing the assemblage of the two halves of the button with each other, and

Fig. 7 is an enlarged detail sectional view of the assembled button.

Referring in detail to the drawings, 5 designates a suitable base in which the lower end of a vertically disposed spindle 6 is suitably fixed. Upon this spindle the die member 7, hereinafter referred to as the lower die, is loosely engaged for vertical movement. The spindle 6 is provided in one side thereof with a longitudinally extending groove or keyway 8 in which the end of a screw 9 threaded in the hub of the die member 7 is engaged to limit the upward movement of said die member under the action of the coil spring 10. In the normal position of this die member it will be observed that the upper end of the spindle 6 protrudes into a central cavity 11 of the die member which is surrounded by a horizontal shoulder 12, said shoulder in turn being surrounded by the upstanding flange 13.

The complementary upper die member 14 is vertically movable upon a spindle 15 in axial alignment with the spindle 6, said spindle 15 however, being mounted in a movable arm or other part indicated at 16 which is operated by a foot treadle, or power mechanism as desired. This spindle is likewise provided with a keyway 17 to receive a stop screw 18 carried by the die member and whereby movement of said die member relative to the spindle is properly limited.

One end of a latch arm 19 is pivotally connected in any suitable manner as at 20 with the spindle 15 above the die member 14. The lower end of said die member is formed with portions of successively reduced diameters providing outer and inner annular shoulders 21 and 22 respectively thereon, the purpose of which will be hereinafter referred to. For the particular kind of button which the mechanism is designed to assemble, the upper end of the spindle 6 is provided with a convex end face 23 while the spindle 15 at its lower end has a complementary concave end face 24, said latter spindle being also provided with an axial bore 25 communicating with the cavity 24.

The die member 14 is also formed with an annular outwardly projecting shoulder 26 thereon which is adapted to be received in the notch 27 provided in the inner edge of the latch arm 19.

In conjunction with the lower die mem-

ber 7 and the upper die member 14, a separate reversible die member is adapted to be used. This latter die member generally indicated at 28 has an axially extending bore 29 terminating at each of its ends in a bevel or flare 30. Each end of said die member is likewise provided with a horizontal shoulder 31 surrounding said bevel and an annular longitudinally projecting flange 32 at the outer side of said shoulder. Said die member is further provided at each of its ends with a laterally extending annular flange 33. Within the bore 29 of the die member 28 a rod 34 of appreciably less length than the length of said bore is loosely engaged for sliding movement, such sliding movement of said rod in each direction being limited by the screw 35 threaded in said die member and engaged at its inner end in the longitudinal groove 36 provided in one side of said rod. This rod at each of its ends is also formed with a concaved face 37.

As shown in Fig. 7 of the drawings, the button consists of a cup-shaped sheet metal front section 38 having an imperforate wall and a similar sheet metal back section 39 of larger diameter, the wall of which is centrally provided with the opening 40. Each of these sheet metal sections is adapted to be covered by the fabric material indicated at 41 and 42 respectively, and in the assemblage of the two metal parts as will be presently explained, the edges of the covering material 42 on the back section 39 of the button are turned inwardly around the edge of the wall of said back section and said covering material and the edge of the metal wall are bent inwardly and clinched upon the rearwardly projecting edge of the front section 38 of the button and the covering material thereon. The two sections of the button with the sheets of the covering material are assembled in the following manner by means of the die mechanism above described.

Initially, one of the front metal button sections 38 is arranged upon the upper end of the spindle 6 within the cavity 11 of the die member 7 and the disc of covering material 41 is then placed over said cavity with its edge resting upon the horizontal shoulder 12 of the die member. The reversible die member 28 is then arranged with one of its ends seated upon the upper end of the lower die member 7, the flange 32 on the end of said reversible die member fitting within the flange 13 of the die member 7 as clearly shown in Fig. 1 of the drawings. The upper die member 14 may then be moved downwardly upon the upper end of the die member 28 or if desired, the latter die member may be forced downwardly by hand pressure so that the lower die member 7 is moved downwardly on the spindle 6 against the action of the spring 10. As a result thereof,

the metallic button sections 38, together with the covering material 41 are forced upwardly into the bore of the die member 28, the rod 34 in the latter die member moving in said bore to the position shown in Fig. 2 of the drawings where it will be noted that the concave face 37 at one end of said rod constitutes substantially a continuation of the beveled or flared surface 30 on the end of the die member 28. The button section and the covering material folded thereover are disposed within the cavity at the other end of said rod.

After the above operation, the die member 28 is removed and the back metal section 39 for the button is then arranged over the upper end of the post 6 and a second disc of covering material 42 is disposed over said button section and upon the shoulder 12 of the die member 7. The upper die member 14 is now lowered with its flange 26 engaged in the notch 27 of the latch arm 19 so that said die member cannot move axially with respect to the spindle 15. As shown in Fig. 4 of the drawings, as the die member 14 is forced downwardly from the position shown in Fig. 3, the said button section 42 and the covering material are forced upwardly into the bore 25 of said upper die member so that the covering material is folded smoothly over said metal section and forced into the cavity 24 on the lower end of the spindle 15. The bore 25 prevents any cushioning effect by such air as may be contained within the lower end of the bore of the die member. Thus, it will be understood that the front section 38 with the covering material 41 therein is now contained in one end of the die member 28, while the back section 39 of the button with the covering material thereon is contained within the bore of the upper die member 14.

In the next operation, another front section 38 is arranged on post 6 and a covering disc 41 disposed in the upper end of the die member 7 and the die member 28 is now again arranged upon said die member 7 but in the reverse position to that which it formerly occupied, or in other words, it is turned end for end. The upper die member 14 containing the covered section 39 of the button is then again forced downwardly, and in this downward movement of said die member, as it comes into engagement with the upper end of the die member 28, the lower end of the latch arm 19 strikes the upper flange 33 on the die member 28 and disengages said latch arm from the flange 26 on the die member 14. Thereafter, the spindle 15 moves downwardly through the die member 14 until the edge of the button section 39 engages the beveled or flared face 30 on the die member 28, at which time the two die members 14 and 28 together with the lower die member 7 are moved down- 130

wardly as a unit on the spindle 6 so that the button section 38 on the upper end of said spindle with the covering sheet 41 is forced upwardly against the lower end of rod 36 in the die member 28, thus forcing the button section 38 and its covering material engaged against the upper end of this rod upwardly in the bore 29 as shown in Fig. 6 of the drawings. Finally, there is an additional downward movement of spindle 15 through the bore of the upper die member 14 so that the projecting edge of the covering material 42 on the button section 39 striking upon the inclined or flared surface 30 is turned inwardly and the edge of said metal button section is also forced inwardly into tight clamping engagement upon the edge of the covered button section 38, thus completing the assemblage of the button as shown in Fig. 7 of the drawings. It will be noted that in this final operation, the flange 32 on the upper end of die member 28 is seated against the inner shoulder 22 of the die member 14, whereas in the operation illustrated in Fig. 3, the outer shoulder 21 provides a seat for the flange 13 on the lower die member 7. Thus, it will be seen that although the opposite ends of the reversible die member 28 are of identically the same construction, either one of said ends will properly cooperate with the differently formed ends of the upper and lower die members 7 and 14.

Since in the final operation shown in Fig. 6 wherein the two covered parts of the button are assembled, another button part 38 with its covering material 41 is positioned in the bore of the die member 28, it will be apparent that thereafter, only the two operations as shown in Figs. 4 and 5 will be required to complete the assemblage of each button.

In the button assembling devices of this kind now known in the art not provided with my improved intermediate reversible die member, three separate and distinct operations are required to assemble the parts of each of the buttons. It will thus be evident that by means of my invention, quantity production of buttons of this type will be largely increased, while at the same time manual labor will be appreciably reduced.

I have herein shown and described an embodiment of my invention which has given excellent results in practice. However, it is

evident that it is possible by resorting to certain more or less obvious modification, to also utilize my present improvements for assembling the parts of buttons of other detail form than that particularly illustrated in Fig. 7 of the accompanying drawings. Accordingly, it is to be understood that I reserve the privilege of incorporating the essential features of my present disclosure in various other structural forms as may be fairly included within the spirit and scope of the invention as claimed.

I claim:

In die mechanism for assembling buttons, upper and lower die members, a fixed spindle upon which the lower die member is vertically movable, a spring yieldingly sustaining the latter die member, a vertically movable spindle upon which the upper die member is loosely mounted, means limiting the axial movement of said die members relative to the respective spindles, latch means to prevent axial movement of the upper die member on its spindle when said die members are brought together whereby the button parts in the lower die member are projected by said fixed spindle into the bore of the upper die member, and a separate die member adapted to be reversibly positioned between the upper and lower die members in different assembling operations, said latter die member having a longitudinal bore and having opposite end portions of the same cross sectional form, each including an inner annular beveled clinching surface, said end portions adapted to cooperatively engage the upper and lower die members, said separate die member being also provided at each of its ends with means for automatically releasing the latch means for the upper die member in the downward movement thereof, and an element movable in the bore of said separate die member to project the button part therefrom, and said separate die member at each end having means one of which is adapted to be engaged by the button part in the bore of the upper die member as it is forced downwardly by the movement of said upper spindle in said bore whereby said button part is contracted upon and assembled with the button part in the bore of said separate die member.

In testimony that I claim the foregoing as my invention, I have signed my name hereto.

MAX MENKIN.
